ELECTRIC WEINER COOKER

Michael Savio, Clifton Heights, Pa.

Application December 20, 1956, Serial No. 44,262

Term of patent 7 years

(Cl. D81—10)

I claim:

The ornamental design for an electric weiner cooker, as shown.
